UNITED STATES PATENT OFFICE.

EDWARD F. MCINTYRE, OF WICHITA, KANSAS, ASSIGNOR TO ANTI-AUTOMOBILE THIEF
ASSOCIATION OF AMERICA, OF WICHITA, KANSAS, A CORPORATION OF KANSAS.

DESIGN FOR AN ASSOCIATION EMBLEM-PLATE.

56,670.

Specification for Design.

Patented Nov. 23, 1920.

Application filed August 29, 1919. Serial No. 320,750. Term of patent 14 years.

To all whom it may concern:

Be it known that I, EDWARD F. MCINTYRE, a citizen of the United States, residing at Wichita, in the county of Sedgwick, and State of Kansas, have invented a new, original, and ornamental Design for an Association Emblem-Plate, of which the following is a specification, reference being had to the accompanying drawing, forming part thereof.

The figure is a plan view of an association emblem plate showing my new design.

I claim:

The ornamental design for an association emblem plate as shown.

EDWARD F. MCINTYRE.
